UNITED STATES PATENT OFFICE.

CHESTER JOSEPH DU MOND, OF PUEBLO, COLORADO.

BUOYANT DRUM FOR MOTOR-PONTOONS.

1,360,101.

Specification of Letters Patent. Patented Nov. 23, 1920.

Application filed November 19, 1918. Serial No. 263,183.

To all whom it may concern:

Be it known that I, CHESTER JOSEPH DU MOND, a citizen of the United States, residing at Pueblo, in the county of Colbert and 5 State of Colorado, have invented new and useful Improvements in Buoyant Drums for Motor-Pontoons, of which the following is a specification.

This invention relates to a buoyant drum 10 for a motor pontoon, and one object is to provide a drum which shall be of light construction but especially adapted to support considerable weight, and also adapted to resist strains incident to the use of the drum 15 as a driving element, for imparting motion to the pontoon.

A further object is to provide a drum which shall be divided into compartments, and which shall be provided at the ends 20 thereof with bracing means of novel construction and unusual efficiency.

A still further object is to provide bracing means at the ends of the drum which shall comprise angle elements reversely mounted 25 and having their arms extending radially of the axis of the drum, the angle elements being connected by curved braces of angular cross section.

With the foregoing and other objects in 30 view, the invention consists in the novel construction, combination and arrangement of elements hereinafter described and claimed.

In the drawings,

Figure 1 is a vertical transverse section of 35 one of the drums, and Fig. 2 is a longitudinal section, the middle portion being broken away.

The shaft 85 of the drum carries disks 90 keyed to the shaft and reinforcing the plates 40 91, the latter being secured by rivets 92 to the heads of the drum, designated 89. This provision in combination with the specific interior construction of each drum hereinafter explicitly set forth, will serve to prevent 45 the imposition of undue torsional strain on the shaft as will be readily appreciated.

It will be noted that the heads and cylindrical wall of the drum are connected by rivets or other suitable means to corner angle 50 irons 93; also, that angle irons 94 of general dihedral configuration are arranged against the heads, with their bights opposed to each other at opposite sides of the drum center and with their outer end portions 55 riveted or otherwise connected in lapped

relation to the angle irons 93. The angle irons 94 are riveted to the heads and their inwardly directed portions serve for the rivet connection of the partitions 95, which are of the same general configuration in 60 cross section as the angle irons 94. In combination with the angle irons 94 and the partitions 95 I employ short curvilinear angle irons 96 and short curvilinear partitions 97. The angle irons 96 are riveted to 65 the heads of the drum, and the partitions 97 are riveted to the inwardly directed portions of the said angle irons, and both the angle irons 96 and the partitions 97 are riveted at their ends to the partitions 95 and 70 the angle irons 94. By virtue of the construction just described it will be manifest that a stiff and strong drum is provided, and one that will not be incapacitated by the incidental formation of a puncture in any 75 wall thereof. Should a puncture be formed in the drum only one compartment thereof will be occupied by water and this will not seriously interfere with the floatability of the drum and will not interfere materially 80 with the floatability or the portability of the pontoon as a whole.

It will also be noticed that the adjacent reinforcing plate 91 and the adjacent head of the drum serve for the connection of the 85 brackets bearing the sprocket gear wheel 88 by means of which the drum is driven.

In conclusion, I would have it understood that with a view to contributing to the lightness and buoyancy of the pontoon without 90 seriously detracting from the stiffness and strength thereof, it is my purpose to construct such parts of the pontoon of aluminum as are suitable for the use of such material.

I would further have it understood that 95 each of the drums of the pontoon is provided on its perimeter with blades or paddles 99, calculated to enable the drums to take positive hold of the water and in that way contribute to the propelling capacity of the drums.

It is the intention that the partition elements shall coöperate with the other bracing elements, for maintaining the drums rigid, 105 and that the drums shall have sufficient buoyancy and rigidity to carry the hull above the water line, as shown in Fig. 2, when the pontoon is in motion, the drums by virtue of their rotation having a tendency 110

to lift the hull to a certain extent and thus add to the effect produced by their buoyant action.

What is claimed is.

- 5 1. A drum for the purpose described, comprising a cylindrical wall, heads, corner angle irons that describe parts of a circle and are riveted to the heads and the cylindrical wall, dihedral angle irons connected to the
- 10 first-named angle irons at their ends and having their bights spaced apart in opposed relation, partitions of similar configuration riveted to the inwardly reaching portions of the dihedral angle irons, curvilinear angle irons riveted to the heads and disposed between the inner portions of the dihedral angle irons, and curvilinear partitions connected to the curvilinear angle irons and
- 15

arranged between the dihedral partitions; said curvilinear angle irons and partitions 20 being connected through the dihedral angle irons and partitions.

2. A drum for the purpose described, comprising heads and a cylindrical wall, dihedral angle irons and partitions fixed in 25 the drum, curvilinear angle irons and partitions fixed in the drum and to the first-named angle irons and partitions, and disks and reinforcing plates fixed to the heads of the drum, in combination with a shaft 30 extending centrally through the drum and to which the disks at the ends of the drum are fixed.

In testimony whereof I affix my signature.

CHESTER JOSEPH DU MOND.
